LAMP-TABLE

Trinie G. Reiter, 3405 Woodbine Ave.,
Baltimore, Md. 21207

Filed May 18, 1972, Ser. No. 254,830

Term of patent 14 years

Int. Cl. D6—03

U.S. Cl. D6—177

FIG.1

FIG. 2

FIG. 3

FIG. 4

FIG. 1 is a perspective view of a first embodiment showing the top and two sides of the invention; the remaining two sides are identical with the respective sides shown to which they are opposed;

FIG. 2 is a plan view, reduced in scale, showing the bottom aspect of the invention.

FIG. 3 is a perspective view of a second embodiment showing the top and two sides of the invention; the remaining two sides are identical with the respective sides shown to which they are opposed;

FIG. 4 is a plan view, reduced in scale, showing the bottom aspect of the FIG. 3 embodiment of the invention.

The invention is characterized by the provision of pile-like covering on the top and sides surmounted by a transparent plate on the top.

I claim:

The ornamental design for a lamp-table, as shown and described.
